UNITED STATES PATENT OFFICE.

JOHN MIKENAS, OF AMSTERDAM, NEW YORK.

MOP HOLDER.

Application filed April 15, 1922. Serial No. 553,256.

To all whom it may concern:

Be it known that I, JOHN MIKENAS, a citizen of the United States, residing at Amsterdam, county of Amsterdam, and 5 State of New York, have invented certain new and useful Improvements in Mop Holders, of which the following is a specification.

This invention relates to improvements in holders for the cloths or rags of mops, particularly to a mop-head provided with novel and improved means for holding the cloths or the like.

It is the principal object of my invention to provide a mop head which allows a 15 ready and convenient attachment of the exchangeable mop rags to the head by means of a clamp, which is extremely simple and inexpensive, in such a manner that no part of the mop head or clamp can touch the 20 floor and damage the same.

Another object of the invention is the provision of a mop the handle of which is adapted to readily operate and lock the clamp after the insertion of the cloth in 25 such a manner that a smooth mopping face is presented to a floor.

Other objects and advantages of my invention will become more fully apparent as the description proceeds and will then be 30 more specifically pointed out in the appended claims.

In the accompanying drawing, forming a material part of this disclosure:—

Figure 1 is a perspective view of a mop- 35 head constructed according to the present invention.

Figure 2 is an end view of the device, in 40 cloth engaging position with the handle in place.

Figure 3 is a similar view, with the handle removed, and the parts in position to receive the mop cloth.

The mop-head comprises a wooden base block 10 provided with longitudinally extending substantially V-shaped grooves 11, 11' in its front and rear edges, in the bottoms of which we find the ends of cross bores 12 extending through the block 10 which are bored through the block so as to 45 form inclined guide holes for the lateral bars 13 and 14 of a wire frame including longitudinal bars 15 and 16 connecting the free end of bars 13 and 14 in such a manner that bar 15 is adapted to rest in the 50 bottom of one V-shaped groove 11, while bar 16 projects above the upper edge of block 55

10 in the opposite side thereof, as indicated in Figure 1.

A second frame, composed of side bars 17 and 18 and connecting bars 19, 20 is extending with its bars 17 and 18 through inclined guide holes in the block.

As shown at 21 the end of bar 13 is guided around the loop formed end of bar 16, and in a similar manner, the end of bar 18 65 is guided around the end of bar 19 as indicated at 22.

Intermediate the ends of bar 19 are coiled around said bar, spaced from each other, the ends 23 and 24 of a wire, which is bent to 70 form lateral branches 25 and 26 which are then coiled around a wire 27 as indicated at 28 and 29 to form a loop 30 for the handle 31 which is introduced with its lower reduced end into a suitable socket of the 75 block 10.

The wire 27 has lateral branches 32 and 33 bent as illustrated in Figure 1, the free ends of which are coiled around wire 16 80 near its ends as indicated at 34 and 35.

The device operates as follows:

If a mop-cloth 36 is to be secured to the head, the handle 31 is removed and the parts are brought by the suitable operation of loop 30 into the position illustrated in Figure 3, the mop cloth 36 is then laid upon the bottom face of block 10 and its ends are guided in the manner illustrated in Figure 1 over the bars 15 and 20. The loop 30 is then moved in the opposite direction, which 90 operation will move frame 13, 14, 15, 16 and 17, 18, 19, 20 respectively, so that the bars 15 and 20 respectively will clamp the cloth 36 between the bottom of grooves 11, 11' and bars 15 and 20 respectively.

If now handle 31 is introduced into loop 30 and the socket in block 10 in the manner illustrated in Figure 1 it will securely lock the parts in their mop-cloth clamping position.

It will be clear that no part of the block or metal frame will touch the floor to be cleaned and that therefore any damage to the same is avoided.

Having thus described my invention, what I claim as new, and desire to secure by Letters Patent of the United States is—

1. A mop holder of the class described comprising a perforated base block, clamping frames having portions slidably disposed in the perforations in said block, means for drawing said frames into clamping

engagement with said block to clamp a mop cloth to said block, and a handle for said block adapted upon being inserted in the handle socket to engage and to lock said frames in their mop clamping position.

2. A mop holder of the class described comprising a base-block provided with two pairs of perforations extending diagonally through said block and with V-grooves in 10 the side edges of said block, a pair of bail-like clamping frames, each having its side portions slidably arranged in a pair of the perforations of said block, means connected to the side portions of said frames for drawing said frames into clamping engagement with said block to clamp a mop-cloth to said block, and a handle adapted to engage a socket provided in said block, said handle, when inserted in said socket, cooperating 15 with said frame operating means to lock said means in mop-cloth clamping position.

3. In a mop holder of the class described, a wooden block provided with two pairs of perforations extending diagonally through 20 said block, said block also provided with

V-shaped grooves in a pair of the opposed side faces of the block, a pair of rectangular wire frames having diagonally intersecting side bars sliding in the perforations of said block, and upper and lower bars connecting the side bars of the frame adapted to engage in said V-shaped grooves over a mop cloth placed over the bottom face of said block and over said lower bars, a wire connected with its ends to one of the upper bars of 35 one of said frames and formed into a loop, a second wire connected with its free ends to the upper bars of the other of said frames around which the loop forming wire is clamped and a handle adapted to engage 40 with its reduced lower end a socket in said block and adapted to engage with its shank said loop for allowing a depression of said loop and operation of said frame to clamp the mop cloth smooth against said block 45 and holding the parts in their adjusted position.

In testimony whereof I have affixed my signature.

JOHN MIKENAS.
